UNITED STATES PATENT OFFICE.

CLOISE H. BALDWIN, OF CHERRYVALE, KANSAS.

METHOD AND APPARATUS FOR FEEDING PULVERIZED FUEL.

1,320,963.

Specification of Letters Patent.

Patented Nov. 4, 1919.

Application filed January 26, 1918. Serial No. 214,006.

To all whom it may concern:

Be it known that I, CLOISE H. BALDWIN, a citizen of the United States, residing at Cherryvale, in the county of Montgomery and State of Kansas, have invented certain new and useful Improvements in Methods and Apparatus for Feeding Pulverized Fuel; and I do hereby declare the following to be a full, clear, and exact description of the invention, such as will enable others skilled in the art to which it appertains to make and use the same.

This invention relates to apparatus for feeding fuel to furnaces of various types and more particularly relates to an apparatus for feeding pulverized fuel to furnaces.

Apparatus of various types have heretofore been provided or contemplated for the feeding of pulverized fuel to furnaces and certain types of these feeders consisted in the employment of a suitable character of conveyer which is arranged in a casing or housing and operative in such manner as to carry the pulverized fuel above an outlet and discharge this pulverized material in a shower across an outlet from the casing through which a draft of air is forced by pressure admitted to the casing, usually the draft being projected from a blast nozzle disposed on the side of the casing opposite the feeder outlet so that the air from the blast would cross the shower of fuel in the casing and the lighter particles of the fuel would be carried by the air as a vehicle into and through the discharge outlet of the feeder to a furnace connected to the feeder outlet. These types of pulverized fuel feeders involving the utilization of a blast of air caused to cross the flowing pulverized fuel are subject to certain objections, among which may be mentioned a loss of efficiency owing to the discharge of the air from the blast nozzle in the enlarged chamber of the casing so that the air was caused to move at a comparatively low rate and with less carrying efficiency through the feeder outlet. Another objection to the blast type of apparatus is that the compressed air has such a large per cent. of moisture that upon the expansion of the air in the feeder chamber or casing, the moisture was condensed and would collect on the coal particles and these becoming moistened, would adhere to the walls of the chamber and conveying mechanism and thus materially interfere with the

discharge of the fuel. Again, in this type of apparatus, when it is necessary to interrupt the supply of fuel to a given furnace, this cannot readily be accomplished without entirely cutting off the blast of air and therefore, the destruction of the feeder nozzle where it remains projecting in the interior of the furnace and is subjected to the high temperatures which would result in the destruction of the feeder nozzle in the event that the current of air is lowered beyond such a quantity as will be necessary to keep the discharge nozzle at such a temperature as to resist attack by the heat. In the blast type of feeder, where the air is caused to pass from the discharge nozzle across the shower of fuel, air which must necessarily pass to the feeder outlet, cannot be cut off to the desired degree and so will carry with it, if only partly cut off, a quantity of fuel to the furnace. Again these types of apparatus do not afford a ready means for controlling the quantity of fuel or regulating the mixture of fuel and air to obtain the best results in operation.

In view of the well-known limitations and objections to pulverized air feeders of the type involving a blast of air being directed across a shower of coal dust, it is one of the objects of the present invention to provide a method and improved means for the efficient feeding of pulverized fuel to a series of furnaces by the employment of a suction or injector principle in which a controllable volume of air is discharged into a feeder outlet leading to a furnace so that a suction is produced in a conveyer housing or casing and by which suction a controllable quantity of the powdered fuel is drawn from the feed chamber or mechanism into the injector or feeder nozzle and thence delivered into the furnace.

Another object is to provide in a pulverized fuel feeding system for the reduction or elimination of the feed of fuel from the conveyer to any one of a series of furnaces when desired without endangering the fuel feeder nozzle to destruction by the heat by supplying a sufficient quantity of air to the nozzle without the conveyance of fuel through the nozzle which it is desired to temporarily cut out.

Another object of the invention is to provide for the control of the tendency of the suction blast to create a vacuum within the apparatus and to provide for the entrance

of the necessary quantity of air into the apparatus in the event that the structure may be of such tight construction as not to inherently admit of a flow of air into and 5 through the conveyer and feeder housing.

With the above and other objects in view as will be rendered manifest in the following specification and which will be clearly comprehended by those skilled in the art, 10 the present invention consists in the method of and means for feeding pulverized fuel to furnaces by the utilization of a suction of air and a device to provide for the suction effect and further consists in the whole, 15 the construction, the combination, the elements and in details and parts more fully hereinafter described, one embodiment of the apparatus and embodiments of details of modified form being illustrated in the 20 accompanying drawings, in which,

Figure 1 is a vertical transverse section through a system in which the present invention is incorporated,

Fig. 2 is a vertical section through the 25 feeder housing and longitudinally through a portion of the conveyer casing,

Fig. 3 is a diagrammatic view illustrating a system showing a pair of furnaces in connection with the conveyer housing and supply for the pulverized fuel,

Fig. 4 is a plan view of a detail at one form of the discharge nozzle support,

Fig. 5 is a cross sectional view on line 5—5 of Fig. 1, showing one form of air blast 35 nozzle,

Fig. 6 is a plan view of a form of valve for controlling the nozzles,

Fig. 7 is a modified form of nozzle construction,

40 Fig. 8 is a sectional detail view of a modified form of the feeder head and

Fig. 9 is a detail view in side elevation of a modified form of fuel carrier.

While the present invention may be utilized in a system of any suitable construction for feeding a pulverized fuel to a furnace or furnaces, it is illustrated diagrammatically in Fig. 3 as involved in an organization comprising a fuel bin B from the 45 bottom of which leads a conveyer housing C in which there is rotated any suitable form of conveyer, as for instance, a screw, not shown, whereby the pulverized fuel is carried from the bin to one or more feeder 50 units F of suitable construction disposed in the conveyer line C and from each of which units there is extended a feeder head H, Fig. 1, from which leads a nozzle N to a respective furnace of a boiler, for instance, A.

Within each of the feeders F is arranged any suitable device for carrying the coal dust upwardly and discharging it in a shower across the outlet O of each feeder, 65 this device being illustrated in Fig. 1 as a

conveyer system comprising an endless chain of buckets 2 mounted in any suitable manner on a sprocket wheel 3 which is secured on the worm or screw shaft 4 which is extended through the conveyer housing C, 70 the endless conveyer 2 being arranged in a casing which forms the unit F and comprises in one form a head member 4 covering an upper sprocket 5 over which the conveyer or bucket belt 2 runs, the head 75 being detachably connected to an intermediate section of the housing 6 which has a removable bottom 7 the latter being provided with a tap-hole 8 at the bottom to provide for the removal of any obstacle or 80 accumulated debris at the bottom of the casing of the feeder unit. A modified form of device for discharging the coal in a shower within the feeder across the outlet O therefrom, is shown in Fig. 9, as comprising a substantially circular bucket wheel 2' which is concentrically fitted upon the conveyer screw S in the housing and is adapted to pick up the coal dust from the bottom thereof and carry it upwardly and 90 discharge it at one side on a level approximately the same as the center of the outlet O.

The operation of the device thus far described is rendered substantially continuous 95 in that pulverized fuel is led from the bin B and carried by the conveyer device in the casing section C to each of the feeder units therein, the excess material or that portion not passing into the outlet from the feeder unit being advanced by the conveyer to one end thereof where it is elevated by any suitable elevated or other conveying device illustrated at E, and thence returned by an upper conveyer G to the bin. 100

The present invention resides more particularly in the provision of means and in the method of causing the transference of the pulverized fuel from the conveying and feeding device to the furnace or furnaces 110 at the boilers A and the mechanism for accomplishing this is illustrated as comprising the head H which may be detachably connected to the outlet member O and has connected to it a tube or pipe forming the 115 feed nozzle N leading to the furnace or fire box. The transference of the fuel through the head H, I preferably accomplish by the production of a suction in the head H which communicates with the chamber of its feed unit casing through the outlet O thereof, and this suction of air in the head H therefore inducts a quantity of the pulverized material which is showered across the outlet from the feed unit into the 120 nozzle head H and thence through the nozzle to its associated furnace.

One form of device for securing this induction effect and the injection of the fuel dust from the nozzle into the furnace is 130

shown in Fig. 1 as comprising a series of relatively independent discharge pipes 10 as shown connected to a base plate 11 which is provided with a series of apertures, one 5 each for the air pipes 10, the base plate being detachably mounted against a seat on the head H and secured there by a clamping disk 12 threaded into a threaded portion 13 of the head H. To control the 10 passage of air from the disk or base plate 11 to each of the air tubes or pipes 10, I provide any suitable form of valve or gate here shown as comprising a short tubular member 17 having a flange 15 the shoulder 15 of which is engaged by a gland 16 which threads to the threaded part 13 of the head to hold the valve member 17 with its upper end bearing snugly against the lower surface of the pipe base 10, this valve member 20 having its upper end rabbeted through an arc of approximately 180 degrees or co-extensive with the arc of apertures to which the ends of the pipes 10 are connected in the base 11 so that by turning the valve 25 member 17 as for instance, by a lever 18 connected thereto, each of the apertures in the base 11 for the pipes 10 may successively be cut off to control the discharge of air 30 through the pipes, the supply of air coming from a pipe 20 extending upwardly from a T-connection 21, the upper end of which pipe 20 is fitted within the turnable valve member 17, the lower end of which is provided with a gland 22 fitting the pipe 35 20. There is shown in Fig. 7 a slightly modified form of air pipe construction in which 10' represents a series of concentric air pipes through which air may pass from the source of supply into the head H and 40 nozzle N of the injector.

By means of the air supply and air control means above described, it will be seen that the amount of fuel induced to enter the feeder head H may be readily determined 45 by the control of the supply of air to the air pipes 10 and moreover, it will be seen that the amount of coal passing into the head H will remain substantially in constant ratio or proportion throughout the entire 50 range of operation of the feed controller which includes the valve member 17, so that when only a small proportion of fuel is desired, it will be clear that the suction effect in the feeder head will be reduced in 55 proportion by the cutting off of the air feed pipes 10 and when a larger proportion of fuel is desired, the suction may be increased by the opening of more air pipes 10.

In the event that the system in which 60 the feed unit or units may be organized is constructed so as to be too tight to admit of a flow of air into the casing or housing in response to the suction produced by the injection nozzle, while discharging air there

may be provided a vent or relief gate 6' at 65 any suitable point in the system as for instance, in the side of the casing 6 of a feed unit F opposite the outlet O this vent gate also therefore providing means for access to the interior of the housing or for observation of the action of the parts during 70 operation.

It is desirable that in the event it becomes necessary to cut off the supply of fuel to any of the furnaces connected in 75 the system, sufficient air may be provided to pass to the nozzle projecting into a fire box of a furnace to prevent the destruction of the nozzle by the intense heat and this is readily accomplished by my invention, 80 by the reduction of the suction created in the apparatus through means of an auxiliary valve 25, Fig. 1, which is adapted to seat, for instance, at the edge of an aperture 11^a formed centrally in the base plate 11, 85 this valve being mounted on the upper end of a stem 26 passing down through the pipe 20 and through the connection 21 which is provided with a bushing 27 through which the stem 26 extends and which latter is provided on its ends with a hand wheel 28 whereby the stem may be turned and by reason of its threaded engagement with the bushing 27 forced to move toward or from 90 its seat on the plate 11. 95

Assuming that any or all of the air pipes 10 are being provided with air from the feed pipe 20 and a suction in proportion to the quantity of air passing through the pipes 10 is created in the outlet O, it will be clear 10 that by opening the auxiliary 25 the tension of the air in the head H will be reduced and the quantity of fuel drawn into the head from the feeder will be proportionately lowered as the valve 25 is opened 105 until, if desired, the valve may be opened to such a position as to prevent the induction of any fuel to the head H while at the same time, air may be discharged 110 through the pipes 10 into the feeding nozzle N of the furnace and the latter protected by the air supplied.

While the controlling mechanism is shown in Fig. 1 as disposed in relative close position to the head H of the feeder, there may be instances in which it would be desirable to arrange a manually operated controlling member at a position somewhat remote from the feeder unit and such an exigency may be met in the modified means shown in Fig. 8 115 120 in which the several air nozzles or pipes 10 are extended from the head H to a convenient point readily accessible to the attendant or the operator as also is the auxiliary or relief valve operating stem 26^a. 125

What is claimed is:

1. In an apparatus for feeding pulverized fuel to a furnace or furnaces, a conveyor

system including operating means for continuously advancing the fuel, a feeder, for each furnace, coacting with the said means and operative to advance the fuel and also to shower it in a diverted path, a feeder head for each furnace and connecting it to the conveyer system and having its intake so disposed that the diverted fuel is showered past it, and pneumatic means disposed in each head for discharging air therein to cause induction of fuel and air at the intake, said pneumatic means comprising individually controllable nozzles whereby the quantity and the quality of the mixture may be varied without variation of the feed by the conveyer system.

2. In an apparatus for feeding pulverized fuel, a conveyer system, a feeder head having its intake so connected as to receive fuel therefrom, and means for discharging a variable amount of air into said head to cause induction at the intake end thereof comprising, a source of air supply, a plurality of pipes connected to said supply and having their discharge ends disposed toward the discharge end of said feeder head and a valve for closing any desired number of said pipes.

3. In an apparatus for feeding pulverized fuel, a conveyer system, a feeder head having its intake so connected as to receive fuel therefrom, and means for discharging

a variable amount of air into said head to cause induction at the intake end thereof, comprising a source of air supply, a base plate disposed at the end of said air supply, a plurality of openings in said plate, pipes connected to said openings, and having their discharge ends disposed within, and opening toward the discharge end of said head, and a valve on said plate adapted to close part or all of said openings.

4. In an apparatus for feeding pulverized fuel, a conveyer system, a feeder head having its intake so connected as to receive fuel therefrom, means for discharging a variable amount of air into said head to cause induction at the intake end thereof and means for relieving the induction at the intake end of said head while air is being discharged therein whereby the discharge end of said head may be cooled when the fuel is not being fed.

5. In an apparatus for feeding pulverized fuel, a conveyer system, a feeder head having its intake so connected as to receive fuel therefrom, means for discharging a variable amount of air into said head to cause induction at the intake end thereof, and auxiliary means for discharging air into said head to counteract the induction in and for the purpose described.

In testimony whereof I affix my signature.
CLOISE H. BALDWIN.
